7-7-3-

7-7-6-

7-7-7-

FIG. 1 is a perspective view of a slide viewer and stand therefor embodying my new design;

FIG. 2 is a perspective view thereof with the viewer being rotated to an inverted or stored position;

FIG. 3 is a front elevational view of the viewer and stand therefor in the configuration shown in FIG. 1;

FIG. 4 is a left side elevational view thereof;

FIG. 5 is a rear elevational view thereof;

FIG. 6 is a top plan view thereof; and

FIG. 7 is a bottom plan view thereof.

I claim:

The ornamental design for a slide viewer and stand therefor, substantially as shown and described.
